James B. Ladd

ATTORNEY

UNITED STATES PATENT OFFICE.

JAMES B. LADD, OF ARDMORE, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

CASTING-LADLE MECHANISM.

Application filed September 15, 1921. Serial No. 500,848.

To all whom it may concern:

Be it known that I, JAMES B. LADD, a citizen of the United States of America, and resident of Ardmore, in the county of Montgomery, in the State of Pennsylvania, have invented a certain new and useful Improvement in Casting-Ladle Mechanism, of which the following is a true and exact description, reference being had to the accompanying drawings, which form a part thereof.

My invention relates to casting ladle mechanism and has for its object to provide a mechanism which will insure a flow of molten metal of constant head and volume from the casting ladle to a mold.

My invention is of a special value and importance for use in connection with centrifugal casting machines of the type described in the German patent to Briede, No. 242,307 of January 4, 1912, and in my co-pending application filed September 13, 1921, Serial No. 500,331, I have described and shown casting ladle mechanism adapted to maintain a constant head and volume of flow in a ladle held stationary while pouring in combination with a casting machine of the type indicated and claimed in this combination. My present invention has to do with a special type of mechanism for securing the kind of flow indicated and as such ladle mechanism is of use and value apart from the centrifugal casting mechanism I have not specifically limited my claims to the combination of the described mechanism with any particular form of casting machine.

The leading feature of my present invention consists in providing the casting ladle with a reservoir from which metal can be poured into it with a float supported on the metal in the casting ladle and with mechanism actuated by the up and down motion of this float for controlling the flow of metal from the reservoir to the ladle.

My invention will be best understood as described in connection with the drawings in which it is illustrated and in which—

Figure 1 is a side elevation partly in section of one form of mechanism embodying my invention, and

Figure 2 is also a side elevation partly in section of modified form of mechanism also embodying my invention.

Referring first to Fig. 1, AA, is one of two standards for supporting the ladles and co-acting mechanism, these standards being

connected together by a cross framing indicated at AA'. AA³ indicates the trunnion supports at the top of the standards AA and A⁴ indicates trunnion supports for the casting ladle. C indicates the casting ladle which in this construction is a tipping ladle having a pouring spout C' and trunnions C² by which it is supported on the trunnion supports A⁴. CC³ is a bracket secured to the bottom of the ladle, as shown, and C⁴ an upright standard secured at the rear top of the ladle. DD is a rock shaft secured to the standards AA; DD' an operating lever and DD² a lever secured to the rock shaft DD and connecting by a link DD³ with the bracket CC³, as shown. E is the reservoir ladle having, as shown, a pouring spout E' and trunnions E² by which it is supported on the supports AA³. E³ is a bracket extending out from the bottom of the ladle, as shown. F is a cylinder in which works a piston not shown, connected by a piston rod F² and the link F³ with the bracket E³. G is a pipe connection for fluid under pressure connecting through a valve indicated at G² and a pipe G' with the bottom of the cylinder F. G³ is a lever arm for actuating the valve. H is an exhaust pipe leading from the bottom of the cylinder F and controlled by a valve H', and valve lever H². I is an adjustable rod secured at its bottom to the valve lever G³ and having, as shown, a counterweight I' also attached at its bottom. The upper end of this rod is slotted as indicated at I² and engaged by a pin in the end of lever arm J⁴ pivoted on the standard C⁴ and having a lever extension J³ which, together with a lever arm J² also pivoted on the standard C⁴, are pivotally secured to the upright bar J' extending from the top of a float J which is supported on the fluid metal in the casting ladle.

In operation the casting ladle C in the position indicated in dotted lines is charged with molten metal to a definite and desired height and the reservoir ladle in the position shown in full lines is also charged with molten metal. The piston in the cylinder F is in the bottom of the cylinder and the mechanism controlled by the float J is in the position in which the valve G² is closed. It being desired to begin the pouring of molten metal into the mold the operator by means of the operating lever DD' and the toggle connected lever DD² and link DD³ tilts the

casting ladle to the position shown in full lines from which a stream of definite volume will flow over its lip C'. As the level of the metal in the casting ladle falls the 6 float J will move down with the result of elevating the outer end of the lever arm J⁴ and pulling up the rod I with the result that the valve G² is more or less opened and pressure fluid passed from the pipe connection G through pipe G' to the bottom of cylinder F as the result of which the piston rod F² and link F³ are moved upward, tilting the reservoir ladle and obviously the operation of the float J will so determine the rate 10 of movement of the reservoir ladle that an approximately constant level of metal is maintained in the casting ladle and consequently a constant flow of metal will issue from it.

20 At the end of the casting operation the exhaust valve H' is opened and the lever DD' operated to return the casting ladle to non-pouring position.

Referring next to the modification shown 25 in Fig. 2 a indicates one of two standards supporting the casting and reservoir ladles, these standards being connected together by cross framing indicated at a' and having, as shown, trunnion supports at a³ and a⁴. c indicates the casting ladle supported, as shown, by trunnions a², c², and having a bottom pour orifice c' which is opened and closed by a stopper indicated at k and which is connected by a cross bar k' with a vertical 35 slide k² moving in guideways c³, c⁴, and actuated to raise the stopper k or lower it to a definite degree by toggle levers l and l' and an actuating rod pivoted to these toggle levers and connected at l². e indicates the 40 reservoir ladle supported, as shown, by trunnions resting on the support a³ and in this construction being of the bottom pour kind having a pouring orifice e' at its bottom. n is a stopper, the raising or lowering of which 45 regulates the flow through the bottom pour orifice. This stopper, as shown, is connected by a cross bar n' to the vertical slide n², moving in guideways e², e⁴, and actuated through a rod f² connected with a piston not shown 50 in cylinder indicated at f. g is a pipe connection leading from a source of fluid under pressure and connecting through a valve indicated at g² with pipes g' and g² which in turn connect with the top and bottom of the cylinder f. The valve g² is actuated through 55

a valve lever g⁴ to which is connected adjustable rod i connected in turn with mechanism similar to that described in connection with Fig. 1 and actuated by a float J.

In the construction of Fig. 2 the casting ladle c is filled to a definite height which is that at which the flow will hold the valve g² in initial position. The stopper k is, of course, down as is also the stopper n of the reservoir ladle. When it is desired to begin 60 pouring the toggle levers l, l', are actuated to lift the stopper to a definite height and hold it in this position. Molten metal will then 65 flow through the bottom pour orifice c' and the float J will begin to move downward and 70 coming through the mechanism described and the valve g² will admit pressure fluid through the pipe g' to the bottom of cylinder f with the result that through the described 75 mechanism the stopper n will be raised and metal will pass down through the opening m' in the cover m of the casting ladle. As 80 the level of the metal in the casting ladle moves up and down the position of the valve g² will be shifted with the result that the stopper n will move up and down regulating 85 the flow of metal into the casting ladle in such a way that an approximately constant level will be maintained therein.

Having now described my invention, what 85 I claim as new and desire to secure by Letters Patent, is:

1. In combination with a casting ladle, means for maintaining a constant level of molten metal therein during pouring consisting of a reservoir adapted to deliver molten metal to the ladle, a float resting on the metal in the ladle and means controlled by the up and down motion of the float for regulating the pouring of metal from the 90 reservoir so as to maintain an approximately constant level in the ladle.

2. In combination with a casting ladle, means for maintaining a constant level of molten metal therein during pouring consisting of means for initiating a flow of metal from the ladle, a reservoir adapted to deliver molten metal to the ladle, a float resting on the metal in the ladle and means 100 controlled by the up and down motion of the float for regulating the pouring of metal from the reservoir so as to maintain an approximately constant level in the ladle.

JAMES B. LADD.
